(57) **CLAIM**

The ornamental design for a wedge speaker, as shown and described.

DESCRIPTION

FIG. 1 is a top perspective view of a wedge speaker of the present invention.

FIG. 2 is another top perspective view of the wedge speaker with the front screen removed.

FIG. 3 is a right side elevation view of the wedge speaker.

FIG. 4 is a left side elevation view of the wedge speaker.

FIG. 5 is a front view of the wedge speaker.

FIG. 6 is a rear view of the wedge speaker.

FIG. 7 is a bottom view of the wedge speaker.

FIG. 8 is a rear, bottom perspective view of the wedge speaker; and,

FIG. 9 is another bottom perspective view of the wedge speaker.

The broken lines in the figures illustrate portions of the wedge speaker that form no part of the claimed design.

1 Claim, 9 Drawing Sheets
